DESIGN FOR A STEEL HOUSE

Beaulard J. Compton, Oildale, Calif., assignor of fourteen per cent to Herman M. Price, San Francisco, Calif., fourteen per cent to Serg Besoyan, Delamo, Calif., and fifteen per cent to Ross B. Walker, two and one-half per cent to Leland S. Hooper, and two and one-half per cent to Albert Diel, Bakersfield, Calif.

Substitute for abandoned application Serial No. 80,107, September 26, 1938. This application July 7, 1939, Serial No. 85,907

Term of patent 3½ years

To all whom it may concern:

Be it known that I, Beaulard J. Compton, a citizen of the United States of America, residing at Oildale, in the county of Kern and State of California, have invented a new, original, and ornamental Design for a Steel House, of which the following is a specification, reference being had to the accompanying drawing, forming a part thereof.

This application is a substitute for my abandoned application Serial No. D-80,107, filed September 26, 1938.

Figure 1 is a perspective view of a steel house, showing my new design.

Figure 2 is a horizontal sectional view.

Figure 3 is a perspective view illustrating the opposite end of the design.

I claim:

The ornamental design for a steel house, as shown.

BEAULARD J. COMPTON.
